(57) **CLAIM**

The ornamental design for a motorcycle tire, as shown and described.

DESCRIPTION

FIG. 1 is a perspective view of a motorcycle tire showing my new design;

FIG. 2 is a front view thereof;

FIG. 3 is a top view thereof;

FIG. 4 is a right side view thereof;

FIG. 5 is an fragmentary enlarged front view showing the details of the tread thereof;

FIG. 6 is a section view taken along line 6-6 in FIG. 5; and, FIG. 7 is a section view taken along line 7-7 in FIG. 5.

The broken lines are for the purpose of showing environmental structure only and form no part of the claimed design.
